DESIGN FOR A SHOE SOLE

Martin A. Sweeney, Chicago, Ill., assignor to J. D. Neilson Company, Chicago, Ill., a corporation of Illinois

Application March 14, 1942, Serial No. 106,201

Term of patent 7 years

To all whom it may concern:

Be it known that I, Martin A. Sweeney, a citizen of the United States, residing at Chicago, in the county of Cook and State of Illinois, have invented a new, original, and ornamental Design for a Shoe Sole, of which the following is a specification, reference being had to the accompanying drawing, forming a part thereof.

Fig. 1 is a plan view of a shoe sole, showing my new design.

Fig. 2 is a fragmentary longitudinal sectional view on the line 2—2 of Fig. 1.

Fig. 3 is a fragmentary transverse sectional view on line 3—3 of Fig. 1.

I claim:

The ornamental design for a shoe sole, as shown.

MARTIN A. SWEENEY,
